UNITED STATES PATENT OFFICE

FRANCIS L. COTTRINGER, OF WILLIAMSPORT, PENNSYLVANIA

SUMMARY REGISTER ATTACHMENT FOR AUTOGRAPHIC REGISTERS

Application filed April 18, 1928. Serial No. 271,017.

This invention relates to manifolding or autographic registers, and more particularly to a summary register attachment for autographic registers.

5 In autographic machines as ordinarily constructed a plurality of record sheets or strips are used from which, as the strips are advanced, a slip is taken off for the salesman or office record, to be placed on file, and another 10 for the customer, and in some cases a third slip, which is conducted into a compartment of the machine, to be taken therefrom by the proprietor or manager of the business for use in checking up the customer's or salesman's 15 record. Each section or slip on a continuous strip has noted thereon different items, according to the business in which it is used, for example, in the automobile supply business, Storage Motor Ethyl Oil Grease Acc'es 20 Labor Wash Total and at the end of the day, in order to ascertain the total amount of each item sold or work done, it becomes necessary to add on an adding machine or otherwise the 25 totals of the itemized amounts shown under each item, so as to ascertain the total amount of sales or charges made for work done during the entire day; this being accomplished according to the common practice by adding 30 up the amounts recorded under different headings on the entire day's record slips, or setting down on a separate sheet of paper in a column or columns of figures the totals of the amounts recorded on the day's record slips and adding up the different columns of 35 figures to ascertain the total amount of the day's sales and charges made for work done during the day. This not only involves the loss of considerable time and labor, but involves a chance of error in copying.

40 The main object of my invention is to provide an attachment to ordinary autographic registers, whereby the trouble and loss of time and labor incident to the aforesaid common practice of ascertaining the total amount of sales or charges for work done during a

specified period of time, as shown by the usual full day's record slips, may be obviated and valuable time saved.

Another object is to provide simple and efficient means adapted for attachment to autographic registers of ordinary construction, whereby the results of a day's sales, or the total amount of sales of one or more articles sold and charges for work done during a certain period of time, as shown under different 50 headings by the usual record strips used on autographic registers may be recorded on a separate sheet or paper strip at the same time that an itemized record is made on the usual printed form record strips, so that at the end 55 of a day or specified period of time the total amount of sales of different items recorded on a batch of sales record slips may be easily and quickly ascertained, thereby avoiding the trouble and loss of time and labor incident to 60 the common method of accomplishing this 65 result.

Another object of the invention is to provide a simple and efficient summary register attachment for autographic registers whereby the total amounts only of sales or charges made and recorded as usual under different 70 headings on an entire day's record slips, may be simultaneously recorded on a separate sheet that may be easily and quickly removed 75 at the end of the day for the purpose of severing a summary register slip and adding up the total amount of sales or charges shown thereon in a single column or separate columns of figures under different headings, and 80 which may be replaced without disturbing the regular loading of the machine proper.

Another object is to provide an attachment 85 of the character referred to which is adapted to be applied to autographic registers of different types in common use without in any way disturbing the usual arrangement of sales and customers' record strips, or the means employed for advancing such strips, 90 or in any way interfering with the regular

loading of the machine proper for use from day to day in the usual way.

Another object is to provide a summary register attachment of the character referred to adapted to be operated by and in synchronism with the mechanism used on autographic registers as heretofore ordinarily constructed for advancing the usual record strips.

10 Another object is to provide a summary register attachment of the character referred to, which is inexpensive to make, and which is adapted to be attached to autographic registers of various kinds, as heretofore ordinarily constructed, without disturbing the arrangement of the record strips or the carbon usually employed, or the mechanism for advancing the strips, and which may be easily and quickly removed and replaced without interfering in any way with the regular loading of the machine.

The invention will first be hereinafter more particularly described, with reference to the accompanying drawings, which are to be taken as a part of this specification, and then pointed out in the claims at the end of the description.

In said drawings, Fig. 1 is a plan view of an autographic register of a well-known type, having a summary register attachment embodying my invention applied thereto to illustrate the application of my invention to a machine of that particular type;

Fig. 2 is a side elevation of the machine shown in Fig. 1;

Fig. 3 is a top or plan view on an enlarged scale of the machine shown in Figs. 1 and 2; parts being broken away to expose end-portions of the summary register attachment underneath the writing table; the lid or cover which overlies the carbon sheets used in such machines being turned over toward one side of the machine;

Fig. 4 is an end elevation of the summary register attachment or detachable unit embodying my invention;

Fig. 5 is a section 5-5 of Fig. 4;

Fig. 6 is a detail side view of a modification 50 of the means employed for advancing the total record strip or sheet carried by the summary register attachment;

Fig. 7 is a cation; and

55 Fig. 8 is a plan view of a total record slip detached, showing the amounts of the sales, etc., recorded on the itemized sales record slips in single rows, and the total of the amounts recorded on each row and also the
60 total amount of the separate items as computed at the end of the day in separate columns to show the total amount of each item.

Referring to said drawings, in which the same reference characters are used to denote corresponding parts in different views, the

letter A denotes the casing or housing for the usual record strips and operating mechanism employed in a manifolding or autographic register of a well-known type, the operative parts of which are in all respects substantially identical with the parts embodied in the commercial machine, except the summary register attachment embodying my invention, which is adapted to record on a separate sheet or strip the total amounts of sales or charges recorded from time to time on the usual customers' or salesmen's itemized sales record slips, during a specified period of time, for instance, during a working day; the total or summary record being made simultaneously with but separate and apart from the sales record slips. The machine shown is provided with a plurality of continuous printed form paper strips, to be divided into suitable lengths as indicated thereon to be severed one at a time from the continuous strips, thus providing a customer's itemized sales record slip, and a salesman's itemized sales record slip, one for the use of the salesman and the other for the customer, and in some cases an office or itemized sales record slip which, instead of being cut off, is automatically folded and concealed within the receiving compartment of the casing for use in checking up the sales record slips. The carbon paper or manifold material used in the commercial machine is arranged to travel across the writing table or platen underlying the uppermost record strip, so that anything written on said strip will be transferred to an underlying paper strip or strips; the uppermost strip being exposed through an opening in the lid or cover plate B the length of a slip to be detached when the desired record is made thereon; the carbon sheet or sheets used for transferring entries to an underlying strip being wound in roll form and placed in a housing C which extends longitudinally of the machine frame or casing A at one side thereof; said lid or cover being provided on the opposite side with a depending hinged plate B¹ adapted to engage the underside of lugs A² on the outer side of the casing A, so as to hold the lid or cover down upon the top of the casing with the opening therein overlying the writing table or platen, as shown in Figs. 1 and 2. When it is desired to advance the carbon sheet or sheets so as to expose a new or unused surface when the previously exposed surface has served its purpose, the lid or cover B is released by disengaging the hinged plate B¹ with the lugs A² and turning the lid over, into the position shown in Fig. 3, whereupon the carbon sheet or sheets may be drawn out by hand transversely of the paper strip or strips. The mechanism for operating the sales record slips includes a crank arm or lever D fixed on one end of the feed roll of the register proper for imparting motion thereto. By turning 70

this lever a complete revolution, the paper strip or strips will be advanced by the feed roll or rolls a predetermined distance equal to the full length of a slip to be detached when the desired record is made, and at the end of one revolution the operating handle or lever D will come into contact with a retractible spring-pressed stop E projecting from the outer side of the casing A into the path of movement of said crank arm; said stop being adapted to be moved inwardly out of the path of movement of the operating arm by pressure of the finger of the operator thereon against the force of the spring, when it is desired to again advance the sales record slip or slips, and when such pressure is relieved the spring will cause the stop to recede into the path of movement of the arm so as to arrest its movement at the end of another complete revolution. By these means a step by step movement is imparted to the sales record strip or strips; the distance the strip is advanced at each movement being determined by the length of the slip which is to be cut off. The hinged plate B¹ of the register proper is used in the commercial machine for holding the lid or cover down upon the record strips and interposed carbon sheet or sheets overlying the writing table or platen, as hereinbefore described, and the same device in the present case also serves as a means for holding in place or securing in operative position the total record sheet carrier and operating mechanism embodying my invention, while the crank handle D serves as a means for imparting a step by step movement to the total record sheet, as hereinafter described.

Inasmuch as the autographic register proper is of well-known construction, further description thereof, except in so far as it may be necessary to describe the illustrated application of my invention thereto, appears to be unnecessary. But I desire it to be understood that my invention is not limited in its application to an autographic register of the type shown, or to any particular type, whether using rolls or flat paper, and whether using a front compartment or rolling up the front roll the full length of the ticket, as in machines of different types now on the market, as my invention is designed and adapted for attachment to autographic registers of various types, either in the form shown, or in different forms in which the same underlying principle and mode of operation may be embodied.

In the illustrated machine, the amount written on the uppermost or top strip under each item noted thereon is transferred to a plurality of underlying sales record strips and also to the total record strip for use at the end of the day, or other specified period of time, in computing the total amounts of sales or charges made during the day. The sales record strips are made to suit any items

that the user may wish to print thereon; the sales tickets or slips themselves being drawn to suit the requirements of the customer or the wishes of the merchant or user of the machine.

As shown, the summary register attachment or total record sheet carrier comprises a frame structure having end plates G and G¹ secured upon a base plate of oblong or rectangular form; said end plates supporting a feed roll I and a paper dispensing roll K, which rolls have their bearings in said end plates and are fitted in open-ended slots i and k, respectively, so that they may be easily removed. The feed roller may be slotted longitudinally, as shown, to permit the end of a strip of paper L to be inserted therein so that the strip may be wound thereon; the strip being drawn off the dispensing roll K upon which it is wound, by a step by step movement imparted to the feed roll. On a projecting end-portion of the feed roll, at one end of the casing, is secured the hub M of a rotary tappet device having radial arms m which project from said hub at a tangent to the roll axis, so that as the tappet device rotates the arms m will be brought successively into the path of movement of a pin N projecting inwardly from the crank arm or handle D of the register operating mechanism, so that during each complete revolution of said crank arm the rotary tappet will be given a partial revolution by contact of said pin with an arm of the tappet device. The pin N is fixed on the crank handle D in position to engage the arms of the tappet device successively as the crank arm is revolved. Backward movement of the tappet device under stress of the pull of the feed roll upon the paper strip L when the stud or pin on the crank arm has moved past the point of contact with a tappet arm may be prevented by means of a spring O secured at one end to the outer side of the register casing and having its free end formed or provided with a wedge-shaped member o which engages the arms of the tappet device as they are brought successively into contact therewith and yields to the pressure of the arm as it slides over the inclined surface and then snaps back so that the contacting arm will engage the shoulder formed by the member o the instant the pin or stud on the crank arm passes the point of engagement with the rotary tappet, thus keeping the grand total sheet taut for recording thereon the total amounts recorded on the itemized sales record slips upon each forward movement of the latter. By the described mechanism the total record strip or sheet is advanced step by step just far enough to record thereon the totals of the itemized sales recorded on one of the detachable sections of the sales record strip as the latter is advanced the full length of the section or slip which is to be cut off, and to this end each

section of the sales record strip is of such length that the space left for writing thereon the totals of the sales or charges made during the day is brought over and in alinement with an underlying opening through the writing table or platen, underneath which, when the total record sheet carrier is inserted in proper position in the register casing, lies a cross-bar P which is mounted upon and connects the 5 end plates of the carrier, above and between the feed and dispensing rolls I and K, so that the totals written upon the sales record slips in the aforesaid space will be transferred to the underlying total record sheet, which 10 passes from the dispensing roller to the feed roll over said cross-bar P. As shown, the ends of the shaft of the paper dispensing roll are fitted in the slots k which extend at an oblique angle to the axis of the roll and rest 15 upon the curved bottoms of the slots, and are secured therein by brackets R which span the oblique slots, and have oblong open-ended slots therein to adapt the bracket to straddle set screws or studs projecting from the inner 20 sides of the end-plates G on opposite sides of the oblique slots, whereby the bracket is firmly but removably secured to the end-plates so as to permit the roll to be removed 25 and replaced when desired. The ends of the feed roll shaft are fitted in vertical slots in the aforesaid end-plates and secured in place 30 by brackets R¹ of the same construction as the brackets R, and secured to the end-plates in the same manner. A flat metal spring S, 35 secured at one end to the base plate of the carrier frame, as indicated in dotted lines in Fig. 4, has its free end arranged to bear upon the roll of paper on the dispensing roll K, so as to tension the same and prevent backward 40 movement thereof when the pin on the crank arm disengages an arm of the rotary tappet. The shank of the spring O is adjustably se- 45 cured to the register casing by slot and set screw connection, in order that the spring may be adjusted to cause the arms of the rotary tappet to contact with and slide over the wedge-shaped member of the spring into 50 position to engage the shoulder o before the tappet is released by the actuating crank arm.

The total record sheet carrier, constructed as described, is removably inserted in an opening through one of the side plates of the 55 register casing, as shown, underneath the writing table, which may be cut away transversely thereof, or made in two parts, so as to provide sufficient space between the two parts to receive the cross-bar or platen P which, as before stated, underlies that portion of the sales record strips, on which may 60 be written the total cost of the articles itemized on the detachable sections or slips, so that the totals are transferred to the grand total sheet or summary of the day's total 65 sales; the carrier being held in place within

the casing by the hinged plate B¹ and co-acting lugs A², as before described.

In Figs. 6 and 7 of the drawings is shown a modification of the means employed for imparting rotary movement, step by step, to the paper dispensing roll of the grand total sheet. In this instance a stud or pin T projects radially from the free end of the crank arm H¹ into the path of movement of a plurality or series of pins u which project laterally from one side of a disk U fixed on the outer end of the feed roll I¹, so that during each complete revolution of the crank arm which actuates the mechanism for advancing the sales record strips it will engage 70 one of the pins u and rotate the disk far enough to advance the grand total record sheet the required distance to bring an unused portion thereof into alinement with the space on the uppermost overlying sales record strip 75 on which the total amount of charges or sales of different items is written and the figures transferred to the underlying strips; the grand total being shown in separate columns of figures or a single row overlying the space 80 occupied by the cross-bar or platen P over which the grand total sheet is caused to pass 85 step by step as hereinbefore described.

The utility and advantages of my invention 90 over autographic registers as heretofore ordinarily constructed are obvious. At the end 95 of the day all that it is necessary to do to ascertain the total amount of the day's sales is to remove the total record slip or sheet and add up the different columns. To this end 100 the lid or cover of the register casing is raised and the total record sheet carrier withdrawn through the opening in the side of the casing, whereupon that portion of the grand total sheet on which the day's charges or sales have 105 been recorded may be torn off and the amounts shown thereon computed, thereby obtaining the result of the day's sales and saving much time and expense incident to 110 computing the totals shown on the itemized sales record slips according to present 115 methods.

After removing the summary of the day's work, or the total record slip, for the purpose of computing the total amount shown 120 thereon, the carrier may be again placed underneath the writing table in the register casing ready for another day's work, by first engaging the end of the grand total sheet with the feed roll, as hereinbefore described, and then raising the lid or cover and placing the necessary carbons between the record sheets and lowering the cover and engaging the 125 hinged plate thereon with the lugs on the casing for holding the carrier in place. In some makes of machines the lid or cover is unprovided with the hinged plate and lugs to hold the cover down upon the record strips and carbon overlying the writing table, as in the 130 illustrated machine, and in such cases the car-

rier may be held in place by securing a spring or springs on the outer side of the casing adapted to press against the carrier and hold it in a fixed position within the register casing; such spring or springs being adapted to swing or be moved into position to permit the carrier to be removed and replaced.

Having thus described my invention, what I claim as new and desire to secure by Letters 10 Patent of the United States is:

1. In combination with an autographic register having means for carrying a sales record strip and means for advancing said strip at intervals a predetermined distance 15 for recording successive sales, a summary register attachment whereby totals of amounts recorded on the sales record strip are transferred to a total record strip; said attachment comprising a frame-structure on 20 which is mounted a paper dispensing roll, a feed roll, and an intermediate cross-bar or platen over which is passed the total record strip carried by said roll, and means at one end of the feed roll co-operatively arranged 25 in relation to the sales strip advancing mechanism of the register proper for advancing said total record strip a predetermined distance simultaneously with the advance movement of said sales record strip.

2. In combination with an autographic register having means for carrying a sales record strip and means for advancing said strip at intervals a predetermined distance for recording successive sales, a summary 30 register attachment whereby totals of the amounts recorded on the sales record strip are transferred to a total record strip; said attachment comprising a frame-structure on which is mounted a paper dispensing roll, 35 a feed roll and an intermediate cross-bar or platen over which is passed the total record strip carried by said roll, and means at one end of the feed roll co-operatively arranged 40 in relation to the sales strip advancing mechanism of the register proper for advancing said total record strip a predetermined distance simultaneously with the advance movement of said sales record strip; said frame-structure being removably 45 inserted through an opening in one side of the register casing with platen underlying an opening extending transversely across the writing table of said casing.

3. In combination with an autographic register having means for carrying a sales record strip and means including a hand lever for advancing said strip for recording successive sales, a summary register attachment 50 adapted to carry a total record strip onto which the totals of amounts recorded on the sales record strip may be transferred; said attachment comprising a frame-structure carrying a paper dispensing roll, a feed roll carrying a wheel element actuated by the lever of said sales strip advancing means and

a cross-bar or platen over which the total record strip is passed from the dispensing to the feed roll.

4. In combination with an autographic register having means for carrying a sales record strip and means including a hand lever for advancing said strip for recording successive sales, a summary register attachment adapted to carry a total record strip onto which the totals of amounts recorded on the sales record strip may be transferred; 70 said attachment comprising a frame-structure removably insertable through an opening in one side of the register casing and embodying a paper dispensing roll to carry the total record strip, a cross-bar or platen over which the strip from said roll is passed and a feed roll onto which the strip is fed, said feed-roll having a tappet element on one end actuated by the lever of said sales strip advancing means for advancing the total record strip to predetermined distance simultaneously with the advance movement of said sales record strip.

5. In an attachment for autographic registers embodying means including a hand-actuated lever for advancing the sales record strips at intervals a predetermined distance for recording successive sales, a frame-structure carrying a paper dispensing roll, a cross-bar or platen over which another recording strip is passed from said roll under the sales record strip and a feed roll onto which said another strip is fed; said feed roll having a rotary tappet element on one end with tangential arms adapted to be engaged by said lever when actuated so as to advance said another strip a predetermined distance simultaneously with the advance movement of the sales record strip of the register.

6. In an autographic register having an operating lever, an attachment for advancing an extra sales recording strip a short distance with each longer advance movement of the regular sales strips of the register proper, said attachment embodying a feed roll supported within the register casing and carrying a tappet member on one end embodying a hub with tangentially disposed arms lying in the actuating plane of the register operating lever for engagement therewith on each operative movement so as to be thereby rotated through a small arc with each such movement.

7. In combination with an autographic register having means for carrying a sales record strip and means including an operative lever for advancing said strip at intervals a predetermined distance for recording successive sales, a summary register attachment whereby totals of the amounts recorded on the sales record strip may be transferred to an extra or total record strip; said attachment comprising a frame-structure applied 125 within the register casing and embodying a

paper dispensing roll, a cross-bar or platen over which a paper strip from said roll is passed under the sales record strip and a feed roll onto which said strip is fed, said feed roll carrying a wheel-like member on one end having tangentially disposed arms engaged by the lever of said sales strip advancing means on each operative movement thereof for rotating said feed roll through a small arc with each advance movement of the sales record strip.

In testimony whereof I affix my signature.

FRANCIS L. COTTRINGER.
